Filed Aug. 27, 1959, Ser. No. 57,348

Term of patent 14 years

(Cl. D44—15)

The figure is a plan view of a plate of conventional configuration showing my new design. The section of motif shown is continued around the entire circumference.

The essential feature of my design for a plate or similar article resides in the ornamentation as shown.

I claim:

The ornamental design for a plate or similar article, substantially as shown and described.
